HUBERT MEREDITH-JONES, OF NEW YORK, N. Y., ASSIGNOR OF ONE-HALF TO ARTHUR CAVERNO, OF NEW YORK, N. Y.

ADDING MACHINE.

Application filed May 5, 1916. Serial No. 95,527.

To all whom it may concern:

Be it known that I, HUBERT MEREDITH-JONES, of New York, in the county of New York and in the State of New York, have 5 invented a certain new and useful Improvement in Adding Machines, and do hereby declare that the following is a full, clear, and exact description thereof.

My invention relates particularly to machines adapted for adding figures for any desired purpose, it being applicable not only to the adding of amounts of money, but quantities of any other character.

The object of my invention is to provide an adding machine of great simplicity and which will, nevertheless, have all of the desired functions, but which has in addition many advantages over previous adding machines. A further object of my invention is to provide an adding machine which is capable of being used for column adding, as well as progressive adding without the necessity of operating levers in changing from one number to another in progressive 25 adding. A further object is to provide an advantageous apparatus for operating the counting wheels. A further object is to provide an advantageous and simple means for transferring the movement of the counting keys to the counting wheels. Further objects of my invention will appear from a consideration of the detailed description of the same appearing hereinafter.

While my invention is capable of embodiment in many different forms, for the purpose of illustration I shall only show one form thereof in the accompanying drawings, in which,

Fig. 1 is a plan view of an adding machine made in accordance with my invention;

Fig. 2 is a side elevation of the same;

Fig. 3 is a transverse section of the same;

Fig. 4 is a similar view, showing the machine operating for progressive adding;

Fig. 5 is a similar view, showing some of the parts removed; and

Fig. 6 is a section of a detail.

In the drawings I have shown an adding machine base 1, having a cover 2, provided with a window 3 through which the numbers registered by the adding machine may be observed. On the base 1, there is provided a transverse shaft 4, carrying a plu-

rality of numeral levers 5, having finger-operated keys 6 at their forward ends. These keys 5 are arranged in such a manner as to provide a row 7 giving the odd numbers and a separate row 8 in advance thereof giving the even numbers. At the forward end of each of the keys 7 there is a lower stop 9 which limits the downward movement thereof, and a further stop 10 which co-operates with a stop plate 11 connected by screws 12 to the frame 1 so as to limit the upward movement thereof. Each of the levers 6 is provided at its forward end with a cam 13 which comprises an inclined surface 14 and a vertical surface 15. The cam 13 is arranged to co-operate with a lever 16 supported upon a pivot 17 located on the frame 1, a spring 17^a being provided around the pivot 17 to normally move the lever 16 towards the front of the machine. Inasmuch as the various keys 7 and 8 are located at varying distances from the pivot 17, it will be noted that they will, by their movement, convey to the lever 16 varying degrees of movement. At the other end of the lever 16 there is pivotally connected to said lever a link 18 which in turn is pivotally connected to a sliding bar 19 carrying a rack 20, and arranged to slide in guideways 21 attached to the frame 1. Meshing with the rack 20 there is a gear 22 loosely carried by an intermediate shaft 23, having a collar 24 on its end beyond said gear 22. On the other side of the gear 22 the shaft 23 has fixedly secured thereto a disc 25, which has a spring-pressed pawl 26 Fig. 5 meshing with said gear 22, the purpose of said pawl being to transmit the forward movement of the sliding plate 19 to the shaft 23, but to prevent the transmission of the movement of said plate 19 in a reverse direction. The shaft 23 is supported at one end in a bearing 26^a carried by the frame 1, and at the other end in a bearing 27 carried by one of the guides 21. Said shaft 23, furthermore, carries a plurality of gears 27^a, each of which is connected to a spacing drum 28 in any suitable manner. One of these gears 27 is provided for each of the columns of figures to be utilized. These gears 27 are arranged so as to mesh with corresponding idler gears 29 carried on stud shafts 30, which are located on a plurality of column levers 31

having keys 33, one of which is provided for each of the columns to be utilized. A spring 34 is provided for each of the column levers 31 so as to normally maintain the corresponding key 33 in an elevated position. At their rear ends each of these column levers 31 is provided with a downwardly directed stop 35 co-operating with the frame 1, and a cam surface 36 which co-10 operates with a pawl 37, located on a shaft 38 in the frame 1. Each of the pawls 37 has a spring 39 which normally presses it forwardly so that the other end thereof carrying a catch 40 may be in engagement with a square recess or notch 41 in a notch wheel 42. Each of the notch wheels 42 is located on and secured to a sleeve extension 43 on a counter wheel 44, and between the notch wheel 42 and the counter wheel 44 15 there is a gear meshing with the corresponding idler gear 29. A plurality of such number wheels are provided for the different columns of figures to be utilized, number wheels 46, 47, 48, 49, 50, 51, 52, 53, 20 54, being provided respectively to indicate the places beginning from the units of cents to the millions of dollars. It will be understood, of course, however, that these columns may be used to count numbers without 25 the decimals, in which case the columns will permit the counting of the hundreds of millions. The several counting wheels 44 and attached parts are carried by a shaft 56 supported in bearings 57 and 58 on the frame 1, 30 said shaft having a hand wheel 59 for resetting the same. All of the number wheels 47 and 54 are loose on said shaft but the number wheel 46 is tight on the same. Each of the number wheels 44 is, further- 35 40 more, provided on the side opposite to that on which the gear 45 is located, with a hollow drum 60 having a plurality of V-shaped inwardly directed notches 61 in its inner face, which are arranged to co-operate with a spring 62 so as to convey movement from one number wheel to the adjacent number wheel when this is permitted by the position of the pawls 37. On the outside of each of said drums 60 there is, furthermore, 45 50 provided a cam surface 62^a Fig. 3 which is arranged to co-operate with and withdraw the pawl 37 from engagement with the surface of the number wheel in the adjacent column to the left so as to cause the 55 rotation of said number wheel a distance equal to one number upon each complete revolution of the number wheel to which the cam 62^a is attached.

From the parts which I have thus far described, it will be seen that when counting in a particular column, it is merely necessary to depress the column key 33 corresponding to the column in which the counting is being done, and thereafter press in succession any 60 65 one or more of the numeral keys 6, while

adding in said column. In order to enable the counting to be thus continuously carried out in the particular column after pressing a column key, each of said column key levers 31 is provided with a catch 63 which is arranged to be caught when depressed beneath a plate 64, carried upon pivoted arms 65 by a shaft 66 in the frame 1, a spring 67 being provided on one of the arms 65 so as to normally move the plate 64 towards the rear of the machine. This arrangement is such that when anyone of the column keys 33 is depressed any other column key previously engaged will be released and the column key being depressed will thereupon itself become engaged by the plate 64. 70 75 80

The adding machine is so arranged that it may be used either for column adding or progressive adding. By column adding is meant the adding of a plurality of figures located in a single column and thereafter adding the figures located in succeeding columns from the left to the right, and by progressive adding, the adding of a plurality of figures of large denomination, as for example, the figures on a series of bank checks, by registering on the machine the amount of a particular check beginning with the figure located at the left of the same and registering the other figures successively to the right 90 95 100 105 110 115 120 125 130 of the same and registering the amount of the next check in a similar manner. The parts thus far described, without any further features, are sufficient for the purpose of column adding. In order to enable progressive adding to be accomplished, I provide means for beginning the registration of a particular amount by pressing the column key corresponding to the column in which the figure farthest to the left is located, and then devices which will upon the pressing of each succeeding numeral key release that particular column key and depress the next column key to the right thereof. For this purpose I provide on the shaft 32 a plurality of right angle arms 68 having springs 69 around the shaft 32 to normally hold said arms 68 in the upper position. These arms 68 on the lower ends are provided with a shaft 70 having a segmental hand-wheel 71 at its outer end carrying the letter P at one end of the segmental wheel and the letter C at the other end thereof. The purpose of these two letters is to see that when the hand-wheel 71 has the letter P uppermost, it is in a position indicating that the machine is ready for progressive adding, and when the letter C is uppermost, the machine is in a position for column adding. The movement of this wheel 71 determines the position of a plurality of projections 72, located on the shaft 70 which register with the number levers 5. When the projections 72 are in engagement with the levers 5, they prevent the engagement of

5 pawls 73 located on the shaft 70 with projections 74 located on the under surfaces of the column levers 31, and when the projections are in the other position, such engagement is permitted. Wires 75 connect the pawls 73 respectively with the pawls 37 which are located in the columns to the left of the columns in which the pawls 73 are located.

10 In the operation of my invention, it being assumed the machine is in position for column adding, that is to say, that the segmental hand-wheel 71 arranged with the letter C uppermost, it will be supposed that the 15 person using the machine wishes to add together a column of figures. In adding this column the units of the figures will be added one after another and thereafter the tens and hundreds, etc. Before beginning the addition, the column key 33 corresponding to the units is depressed and is retained in depressed position by the catch 63 thereon engaged with the plate 64. The numbers in the units column are then registered one 20 after another by pressing one after another the number keys themselves corresponding to the same. The movement of a number key produces a corresponding degree of movement in the lever 16 which transmits 25 its movement to the sliding bar 19 and by means of the rack 20 to the loose gear 22, which in turn transmits its movement through the pawl 26 to the shaft 23, the gears 27^a, idler gear 29 located in the units 30 place, and the gear 45 attached to the number wheel 46. When the number wheel 46 has made a complete revolution the cam surface 62^a will engage with the adjacent pawl 37, thereby moving the catch 40 out 35 of the notch in the notch wheel 42, so that the spring 62 on the number wheel 47, engaging with one of the V-shaped notches 61, will move the number wheel 47 a distance from 0 to 1. As the cam surface 62^a 40 passes beyond the pawl 37, the said pawl falls into one of the notches in the wheel 42, thereby preventing the further movement of the number wheel 47 until a further revolution of the number wheel 46 has taken place. 45 When all of the numbers in units place have been added together in this way, the column key 33, corresponding to the tens is depressed. A depression of this key releases the column key in units place because of the 50 movement of the plate 64 from over the catch 63 attached to the column key in units place. At the same time, the depression of the column key in tens place causes it to be retained in depressed position because of the engagement 55 of its catch 63 with the plate 64. In this manner the columns are added up one after another until the entire column of figures has been added together and the total is then read off through the window 3. In 60 case in the numbers in the column added, one

of the columns contains only zeros, the column key for that column is not pressed, but the column key corresponding to the next column to the left is pressed.

When it is desired to do progressive adding, the segmental hand-wheel 71 is rotated so as to bring the letter P uppermost. Assuming now that there are a plurality of amounts to be added together, as for example, the amounts of a plurality of bank 75 checks, and that these amounts are to be registered in succession on the adding machine, and that the numbers in a particular amount are to be registered by registering first the number farthest to the left, and thereafter in succession the numbers to the right of said number, the column key is pressed which corresponds to the figure farthest to the left. This causes said column key to engage with the plate 64 so as to be 80 retained in depressed position, and, at the same time, to move the pawl 37 towards the back of the machine, which, through the wire 75, moves the pawl 73, corresponding to the column immediately to the right of 85 the column in which the said pawl 37 is located, in the same direction so that it overlies the flange 74 located upon the column key 33, immediately to the right of the column key that has been depressed. The 90 number key corresponding to the number in this particular column is now depressed, which on its initial downward movement registers the number on the number wheel 95 corresponding to this column. The downward movement of the number key, through the engagement of the lever 5 with the projection 72, also causes the pawl 73 to be depressed so that the particular pawl 73, which overlies the projection 74 on the column lever 31 next to the right of the column lever which has been previously depressed, is itself depressed, thereby releasing the previously depressed column lever and causing it to be returned to its initial position, but 100 retaining depressed the column lever which has been depressed by the pawl 73. The other columns in succession to the right of the original column registered are thus 105 taken care of in succession until the entire amount has been registered. The next amount, as for example, on the next bank check, is then registered in a similar manner by depressing the column key corresponding to the number farthest to the left in said amount and proceeding as before. In case in any of the amounts there is a zero, no 110 number key is pressed to register this zero, but before registering the next number to the right it is merely necessary to depress the column key corresponding to said number, after which the operator may proceed as before and the same as if there had been no zero present.

115 While I have described my invention 120 125 130

above in detail, I wish it to be understood that many changes may be made therein without departing from the spirit of my invention.

5. I claim:

1. An adding machine having a plurality of number keys and totalizing devices adapted to be actuated by said number keys, comprising a lever adapted to be moved distances varying according to the number keys, said number keys being located at distances from the pivot of said lever proportional to the numerals corresponding respectively thereto, column keys, and means controlled by said column keys for directing the movement of said lever to the desired column.
2. An adding machine having a plurality of number keys and totalizing devices adapted to be actuated by said number keys, comprising a lever adapted to be moved distances varying according to the number keys, said number keys being located at distances from the pivot of said lever proportional to the numerals corresponding respectively thereto, a plurality of column keys, and number wheels, and means whereby the operation of a column key directs the movement of said lever to the corresponding number wheel.
3. An adding machine having a plurality of number keys, and a plurality of column keys, and means whereby amounts each including a plurality of figures may be progressively registered merely by manipulation of the number keys.
4. An adding machine having a plurality of number keys, and a plurality of column keys, and means whereby the manipulation of a number key will render inoperative one column key, and render operative the key of an adjacent column.
5. An adding machine having a plurality of number keys, and a plurality of column keys, and disengageable means whereby amounts each including a plurality of figures may be progressively registered merely by manipulation of the number keys.
6. An adding machine having a plurality of number keys, and a plurality of column keys, and disengageable means whereby the manipulation of a number key will render inoperative one column key, and render operative the key of an adjacent column.
55. 7. An adding machine having a plurality of number keys and a plurality of column keys, and connecting means between said keys, whereby the manipulation of the number key to register a number in one column will depress the column key of the column next to the right thereof.
60. 8. An adding machine having a plurality of number keys and a plurality of column keys, a pawl adapted to be actuated by depression of a number key to register a num-

ber in one column, to depress the column key of the column next to the right thereof, and means whereby said pawl may be removed from operative position.

9. An adding machine having means for adding progressively by registering one amount directly after another, comprising a plurality of column keys, a plurality of number keys, and means for depressing the column key of the column next to be computed by the depression of the number key. 75

10. An adding machine having means for adding progressively by registering one amount after another independently of the manipulation of any lever between succeeding columns, comprising a plurality of column keys, a plurality of number keys, and means for depressing the column key of the column next to be computed by the depression of the number key. 80

11. An adding machine having means for adding progressively by registering one amount after another, comprising a plurality of column keys, a plurality of number keys, means for depressing the column key of the column next to be computed by the depression of the number key, and means for adding in columns. 85

12. An adding machine having means for adding progressively by registering one amount after another, independently of the manipulation of any lever between succeeding columns, comprising a plurality of column keys, a plurality of number keys, means for depressing the column key of the column next to be computed by the depression of the number key, and means for adding in columns. 90

13. An adding machine having means for adding progressively by registering one amount after another, comprising a plurality of column keys, a plurality of number keys, means for depressing the column key of the column next to be computed by the depression of the number key, means for adding in columns, and a device for adjusting the machine for adding in columns or progressively. 105

14. An adding machine having means for adding progressively by registering one amount after another, means for adding in columns independently of the manipulation of any lever between succeeding columns, comprising a plurality of column keys, a plurality of number keys, means for depressing the column key of the column next to be computed by the depression of the number key, and a device for adjusting the machine for adding in columns or progressively. 110

15. An adding machine having means for adding progressively by registering one amount directly after another, comprising a plurality of column keys, a plurality of number keys, and means for depressing the column key of the column next to be computed by the depression of the number key. 125

puted by the depression of the number key and releasing the previously depressed column key.

16. An adding machine having means for adding progressively by registering one amount after another independently of the manipulation of any lever between succeeding columns, comprising a plurality of column keys, a plurality of number keys, and means for depressing the column key of the column next to be computed by the depression of the number key and releasing the previously depressed column key.

17. An adding machine having means for adding progressively by registering one amount after another, comprising a plurality of column keys, a plurality of number keys, means for depressing the column key of the column next to be computed by the depression of the number key and releasing the previously depressed column key, and means for adding in columns.

18. An adding machine having means for adding progressively by registering one amount after another, means for adding in columns independently of the manipulation of any lever between succeeding columns, comprising a plurality of column keys, a plurality of number keys, and means for depressing the column key of the column next to be computed by the depression of the number key and releasing the previously depressed column key.

19. An adding machine having means for adding progressively by registering one amount after another, comprising a plurality of column keys, a plurality of number keys, means for depressing the column key of the column next to be computed by the depression of the number key and releasing the previously depressed column key, means for adding in columns, and a device for adjusting the machine for adding in columns or progressively.

20. An adding machine having means for adding progressively by registering one amount after another, means for adding in columns independently of the manipulation of any lever between succeeding columns, comprising a plurality of column keys, a plurality of number keys, means for depressing the column key of the column next to be computed by the depression of the number key and releasing the previously depressed column key, and a device for adjusting the machine for adding in columns or progressively.

21. An adding machine having a plurality of number keys, a plurality of column keys, a plurality of number wheels, pawls for the number wheels, pawls for the column keys connected to the pawls for the number wheels, projections on the column keys, cooperating with the column key pawls, and a common connecting means for the column

key pawls adapted to be operated by the number keys.

22. An adding machine having a plurality of number keys, a plurality of column keys, a plurality of number wheels, pawls for the number wheels, pawls for the column keys connected to the pawls for the number wheels, projections on the column keys, cooperating with the column key pawls, and a common connecting means for the column key pawls adapted to be operated by the number keys, comprising a shaft with rotary projections.

23. An adding machine having a plurality of number keys, a plurality of column keys, a plurality of number wheels, pawls for the number wheels, pawls for the column keys connected to the pawls for the number wheels, projections on the column keys, cooperating with the column key pawls, a common connecting means for the column key pawls adapted to be operated by the number keys, comprising a shaft with rotary projections, and a hand-wheel with indicating means attached to said shaft.

24. An adding machine comprising a plurality of number keys, an intermediate shaft actuated thereby, a plurality of counter-wheels, gears on said shaft and wheels, idlers for connecting the shaft and wheel gears, and column keys supporting said idlers, movable to throw the same into and out of operative position.

25. An adding machine comprising a plurality of number keys, an intermediate shaft actuated thereby, a plurality of counter-wheels, pawls normally holding said wheels from rotation, and column keys carrying means for connecting a set of shaft and wheel gears and for moving an adjacent pawl out of operative position.

26. An adding machine comprising a plurality of number keys, an intermediate shaft actuated thereby a plurality of counter-wheels, pawls normally holding said wheels from rotation, gears on said shaft and wheels, idlers, and column keys supporting said idlers movable to throw the same into and out of operative position, said column keys having a cam surface for moving an adjacent pawl out of operative position when the column key is depressed.

27. An adding machine comprising a plurality of number keys, an intermediate shaft actuated thereby, gears on said shaft and wheels, idlers for connecting the shaft and wheel gears, and column keys supporting said idlers movable to throw the same into and out of operative position, and a connecting means between said keys, whereby the manipulation of a number key in one column will depress the column key of the column next to the right thereof.

28. An adding machine comprising a plurality of number keys, an intermediate shaft

actuated thereby, gears on said shaft and wheels, idlers for connecting the shaft and wheel gears, and column keys supporting said idlers movable to throw the same into and out of operative position, and a connecting means between said keys, whereby the manipulation of a number key will render inoperative one column key and render operative the key of an adjacent column.

10 29. An adding machine comprising a plurality of number keys, an intermediate shaft actuated thereby, a plurality of counter-wheels, gears on said shaft and wheels, idlers for connecting the shaft and wheel gears, and column keys supporting said idlers movable to throw the same into and out of operative position, a plurality of movable pawls adapted to depress the column keys and normally held away therefrom, and means whereby the depression of one column

key will move the pawl of an adjacent column key into position to engage therewith.

30 30. An adding machine comprising a plurality of number keys, an intermediate shaft actuated thereby, a plurality of counter-wheels, gears on said shaft and wheels, idlers for connecting the shaft and wheel gears, and column keys supporting said idlers, movable to throw the same into and out of operative position, a plurality of movable 35 pawls adapted to depress the column keys and normally held away therefrom and disengageable means whereby the depression of one column key will move the pawl of an adjacent column key into position to engage therewith.

In testimony that I claim the foregoing I have hereunto set my hand.

HUBERT MEREDITH-JONES.
